ORNAMENTAL SEAM SEWING MACHINE

Sydney Zonis, Bridgeport, Conn., assignor to The
Singer Manufacturing Company, Elizabeth,
N. J., a corporation of New Jersey

Application November 12, 1935, Serial No. 49,331

7 Claims. (Cl. 112—81)

This invention relates to improvements in sewing machines and has for its primary object to provide a sewing machine adapted to make open-work seams closely simulating a hemstitch seam 5 and having a work-production capacity which is considerably greater than that of hemstitching machines.

With the above and other more specific objects in view, as will hereinafter appear, the invention 10 consists in the devices, combinations and arrangements of parts hereinafter described in connection with the accompanying drawings which illustrate an embodiment of the invention in a lock-stitch sewing machine.

15 In the drawings, Fig. 1 is a front side elevation, partly in vertical section, of a sewing machine having the improved seam forming mechanism of the present invention. Fig. 2 represents a horizontal longitudinal section of the bracket-arm of the machine. Fig. 3 is a bottom plan view of the machine. Fig. 4 is a front end elevation, partly in vertical section, of the sewing machine, with the bracket-arm face-plate removed. Fig. 5 is a rear side elevation of a portion of the bracket-arm head of the machine. Fig. 6 is a detail view of the feed-lift cam and the rock-arm actuated thereby. Fig. 7 is an enlarged view in side elevation of the feed-lift cam. Fig. 8 is an enlarged view in side elevation of the feed-advance cam. Fig. 9 is an enlarged view in side elevation of the main-piercer actuating cam and of the crank-arm actuated thereby, the piercer rock-shaft being shown in section. Fig. 10 represents a development of the needle-vibrating cam. Fig. 35 11 illustrates the two-stitch open-work seam produced by the present machine.

Referring to the drawings, the present sewing machine has the usual framework including a bed- or cloth-plate 1, from which rises a hollow 40 standard 2 of an overhanging bracket-arm 3 terminating in a head 4. Journaled in suitable bearings provided in the bracket-arm is a horizontally disposed rotary main-shaft 5, carrying at one end a belt-pulley 6 and at its opposite end 45 a crank-disk 7. The crank-disk 7 has a crank-pin 8 connected by a link 9 to a needle-bar 10 journaled for vertical reciprocation in suitable bearings provided therefor in the head 4.

The needle-bar 10 carries at its lower end a 50 supporting plate 11, pivotally sustaining a pair of needle-carriers 12 and 13, secured upon said plate 11 for relative adjustment toward and from each other. The needle-bar carrier 12 is provided with a thread-carrying needle 14 and also 55 a vertically disposed guide-rod 15, while the need-

dle-carrier 13 is similarly provided with a thread-carrying needle 16 and a vertically disposed guide-rod 17. The needles 14 and 16 are arranged abreast with respect to the direction of feed of the work and are adapted to be vibrated toward and from each other to perform, alternately, narrowly and more widely spaced work-penetrating movements.

To this end, the respective guide-rod 15 and 17 are passed through swivel-pins 18 and 19 mounted in crank-arms 20 and 21 carried by the front ends of horizontally disposed and substantially parallel rock-shafts 22 and 23, journaled in the bracket-arm head 4. At their rearward ends, i. e., at the rearward side of the head 4, the respective rock-shafts 22, 23 carry the oppositely directed crank-arms 24 and 25, connected by links 26 and 27 with correspondingly arms of bell-crank levers 28 and 29 fulcrumed adjacent to each other upon the bracket-arm head 4 at the rearward side thereof. The other arms of said bell-crank levers are pivotally connected to the forward ends of horizontally disposed pitman-rods 30 and 31, of which the opposite ends are adjustably connected to a vibratory arm 32, in a manner more fully disclosed in the U. S. patent to A. H. De Voe, No. 1,940,399, Dec. 19, 1933. The vibratory arm 32 carries a cam-stud 33 entering a peripheral groove 34 provided in the cam 35 secured to a spur-gear 36 for rotation therewith upon a stub-shaft 37, said stub-shaft 37 being suitably fixed in the bracket-arm 3, below and substantially parallel to the main-shaft 5. The spur-gear 36 is driven by a pinion 38 secured upon the main-shaft 5 to rotate once for two rotations of the main-shaft.

Complemental to the respective needles 14 and 16, in the formation of lock-stitches, are loop-takers 39 and 40 of the vertical-axis rotary hook type having their needle-thread-loop seizing paths of movement below the cloth-plate and at the relatively remote sides of the needles. The loop-takers 39 and 40 may be of any usual or suitable construction and, in the present machine, are each rotated twice for each reciprocation of the respective needle with which it cooperates. The loop-takers 39 and 40 are driven by spiral-gear connections with a horizontally disposed rotary actuating shaft 41 journaled beneath the cloth-plate and connected by means of a vertically disposed intermediate shaft 42 and suitable gears with the main-shaft 5.

The work is advanced by a drop-feed mechanism comprising a feed-dog 43 operating through a suitably slotted throat-plate 44 secured upon

the cloth-plate 1, said feed-dog being opposed by a presser-foot 45, preferably of the kind commonly employed in hemstitching machines. The feed-dog 43 is carried by a feed-bar 46 pivoted, 5 at one end, to a rocker 47 carried by a feed-advance rock-shaft 48. At its opposite end, the feed-bar is operatively engaged by a rock-arm 49 of a feed-lift rock-shaft 50, said rock-shafts 48 and 50 being journaled in suitable bearings 10 provided at the under side of the bed-plate 1.

The feed-advance rock-shaft 48 carries a crank-arm 51 pivotally connected to the lower end of a link 52, of which the upper end is adjustably secured to a segment-lever 53 disposed outside of the arm-standard and below the bracket-arm. The segment-lever 53 is secured upon a fulcrum-shaft 54 journaled in the bracket-arm standard 2, said segment-lever carrying a roller-stud 55 entering a cam-groove 56 formed in the 20 side face of a feed-advance cam 57. The cam 57 is secured for rotation with the spur-gear 36 which, as hereinbefore described, rotates once for two rotations of the main-shaft. By referring to Fig. 8 of the drawings, it will be observed 25 that the cam-groove 56 is so formed as to impart two work-advancing impulses and two return movements to the feed-dog 43 for each complete rotation of the feed-cam 57. Therefore, as the needles make a complete reciprocation for each 30 rotation of the main-shaft 5, the work is advanced during each of the unison stitch-forming cycles of the needles, the timing being such that the work is advanced while the needles are out of the work.

35 Clamped upon the feed-lift rock-shaft 50 is a crank-arm 58 connected by a link 59 to a rock-arm 60 pivotally mounted upon the fulcrum-shaft 54. The rock-arm 60 carries a cam-stud 61 entering a feed-lift cam-groove 62 in the side 40 face of the spur-gear 36. By referring to Figs. 6 and 7 of the drawings, it will be observed that the feed-lift cam-groove 62 is so formed as to impart two complete vibrations to the rock-arm 60 for each rotation of the spur-gear 36. Consequently, the feed-dog 43 is raised into engagement with the work and is again lowered during each of the unison stitch-forming cycles of the 45 needles, the raising and lowering movements of the feed-dog being, of course, suitably timed to 50 the work-advancing and return movements of said feed-dog.

A main piercer-and-shaper 63 has endwise reciprocal movements between the needles 14 and 16 in a path to enter apertures previously 55 formed in the work and also entered by said needles during their narrowly spaced descending movements, said main piercer 63 being preferably recessed at opposite sides thereof to receive the needles when narrowly spaced. The main 60 piercer 63 is carried by a piercer-bracket 64 secured upon the lower end of a piercer-bar 65 journaled for vertical reciprocation in the bracket-arm head 4. Carried by the piercer-bar 65 is a collar 66 to which is pivotally connected a 65 crank-arm 67 at one end of a horizontally disposed rock-shaft 68 journaled in spaced bearing-lugs 69 and 70 at the rear side of the machine bracket-arm. At its other end, the rock-shaft 68 carries a short crank-arm 71 provided with a 70 follower 72 entering a cam-groove 73 formed in the side face of a peripherally toothed cam or spur-gear 74. The spur-gear 74 is journaled to rotate upon a stub-shaft 75 suitably secured in a bracket 76, attached to the frame arm 3 75 by screws 77. The spur-gear 74 is driven by

a pinion 78 upon the main-shaft 5 to rotate at one half the speed of rotation of said main-shaft.

By referring to Fig. 9 of the drawings, it will be observed that the cam-groove 73 is so formed as to impart one complete reciprocation to the piercer-bar 65 for each rotation of the spur-gear 74. Consequently, the main piercer 63 performs only one reciprocation for two successive reciprocations of the needles 14 and 16. The timing of the main-piercer operation is such that when the needles are in their narrowly spaced relation, the piercer 63 descends to penetrate the work before the descending needles reach the work, whereby the needles may enter the aperture as shaped by said piercer. The piercer 63 begins to rise as the needles are completing their descent, said piercer suspending its operation at the beginning of its subsequent descent to remain ineffective, while out of the work, until the needles have completed their subsequent reciprocation in their more widely spaced relation.

Mounted upon the needle-bar plate 11, so as to be disposed directly in front of the main-piercer 63, is an auxiliary piercer 79, the space between said piercers being preferably equal to, although 25 it may be a multiple of, the amplitude of work-advancing movement of the feed-dog 43. Being carried by the needle-bar 10, the auxiliary piercer 79 reciprocates vertically in unison with the needles. The auxiliary piercer 79 not only functions 30 to initially form an aperture in the work for subsequent entrance by the main piercer 63 but, as hereinafter described, also serves to act upon the cross-bars which separate the apertures of the open-work seam, whereby the product has the 35 appearance of a hemstitch seam in which the longitudinal threads have been drawn previous to the hemstitching operation.

In Fig. 10 of the drawings, which illustrates a development of the needle-vibrating cam 35, the cam-groove 34 is substantially straight from W, marking the beginning of the more widely spaced relation of the needles 14 and 16, to W' which marks the ending of said more widely spaced relation of the needles. From W' the cam acts gradually to move the needles into their 45 narrowly spaced relation in which they remain for an interval before being again spread into their more widely spaced relation.

When the needles are at their upper limit of 50 movement and in their narrowly spaced relation, the feed-dog 43 has substantially completed its work-advancing movement and the work-aperture previously formed by the auxiliary piercer 79 is positioned for entrance by the main piercer 63 which, at this time, is also at substantially the upper end of its path of reciprocation. The needle-bar 10 and the piercer-bar 65 begin their descent at substantially the same time, the main piercer 63 preceding the needles in the entrance 60 of the previously formed work-aperture. The auxiliary piercer 79 descends with the needles and penetrates the work in front of the main piercer, said auxiliary piercer being preferably shaped to push apart the work-threads, extending longitudinally of the seam line, preferably to an extent 65 substantially equal to the width of the work-aperture as shaped by the main piercer 63.

After having entered the work-aperture, the descending needles are moved apart, under the 70 action of the cam 35, into the more widely spaced relation of the needles reached at substantially the bottom of the needle stroke. The main piercer begins to rise as the needles are completing their downstroke, after which the spread 75

needles rise vertically and present needle-thread loops to the loop-takers 39, 40 for the formation of stitches. The needles continue to rise vertically in their more widely spaced relation, the work being advanced by the feed-dog 43 when the needles leave the work and while they are completing their upstroke. The main piercer 63 reaches its upper limit of movement, out of the work, while the needles are completing their upstroke, said main piercer 63 thereupon remaining substantially idle during the succeeding complete reciprocation of the needles. In said succeeding complete reciprocation, the needles descend and rise vertically in the previously attained more widely spaced relation, until after said needles are again out of the work, at which time the cam 35 acts to move the needles laterally into their narrowly spaced relation. Consequently the needles have no lateral movement while in the work during the second reciprocation of the needles. The needle-thread loops are again seized by the loop-takers 39, 40 during the second reciprocation of the needles and the work is again advanced by the feed-dog 43 after the needles leave the work. The auxiliary piercer 79, of course, moves downwardly to penetrate the work while the needles descend the second time above described, and it is the work-aperture formed by the auxiliary piercer 79 in the second descent of the needles which is subsequently entered by the main piercer 63. In its work-penetrating movement during the first descent of the needles, the auxiliary piercer 79 acts upon the cross-bars of the open-work seam, said auxiliary piercer functioning to push the fabric-threads, extending parallel to the seam line, toward the opposite ends of the cross-bars. This function of the auxiliary piercer is aided by the spreading movement of the needles from their narrowly spaced relation. By reason of the fact that the needles in their more widely spaced relation have no relative approaching movement while in the work, said needles have no tendency to return the displaced fabric threads. The non-vibration of the needles in their more widely spaced relation also results in an enhanced appearance of the work arising from the fact that the work-penetration points outside of the piercer apertures are not enlarged and, accordingly, the product of the present machine is free of this defect common to hemstitch seams.

Fig. 11 illustrates one form of open-work seam which may be made by the machine described. A piece of fabric A is provided with apertures *a* initially formed by the auxiliary piercer 79 and subsequently entered and shaped by the main piercer 63. Separating said apertures *a* are cross-bars *b*, comprising fabric threads extending crosswise of the seam, the fabric-threads extending longitudinally of the seam having been spread apart from the middle and toward opposite ends of said cross-bars *b* by the auxiliary piercer 79. The apertures *a* are held open by two rows of zigzag stitches *S*, the successively formed stitches of each row extending divergently from the apertures *a* to points *c* in the fabric A, adjacent to the ends of the cross-bars *b*. The divergent pull of the stitches serves to hold said apertures open.

It will be understood that seams of different appearances may be formed by substituting main piercers of different shapes and sizes and by changing the feed-advance cam to make alternately long and short stitches. It is also to be understood that the present invention is not

limited to lock-stitch machines, as chain-stitch loopers or equivalent devices may be employed for anchoring the needle-threads, instead of the rotary hooks of the present machine.

Having thus set forth the nature of the invention, what I claim herein is:—

1. In a sewing machine, a pair of endwise reciprocatory and laterally vibratory needles, needle-actuating mechanism including means for reciprocating said needles endwise in unison and for vibrating said needles laterally toward and from each other to perform alternate narrowly and more widely spaced work-penetrating movements, means complementary to said needles in the formation of stitches, work-feeding means effective to advance the work for each of the unison stitch-forming cycles of said needles, an endwise reciprocatory work-penetrating piercer having a path of movement to form apertures in the work for entrance by both needles in their narrowly spaced reciprocations, and means for reciprocating said piercer.

2. In a sewing machine, a pair of endwise reciprocatory and laterally vibratory needles, needle-actuating mechanism including means for reciprocating said needles endwise in unison and for vibrating said needles laterally toward and from each other to perform alternate narrowly and more widely spaced work-penetrating movements, means complementary to said needles in the formation of stitches, work-feeding means effective to advance the work for each of the unison work-penetrating movements of said needles, an endwise reciprocatory work-penetrating piercer having its operative path of movement between the needles to form apertures in the work for entrance by both needles in their narrowly spaced reciprocations, and means for reciprocating said piercer.

3. In a sewing machine, a pair of endwise reciprocatory and laterally vibratory needles, needle-actuating mechanism including means for reciprocating said needles in unison and for vibrating said needles toward and from each other to perform alternate narrowly and more widely spaced work-penetrating movements, means complementary to said needles in the formation of stitches, work-feeding means effective to produce an advance of the work for each of the unison work-penetrating movements of said needles, a reciprocatory work-penetrating piercer, and means for actuating said piercer in timed relation with the needle-reciprocations to form apertures in the work for entrance by both of said needles in their narrowly spaced reciprocations and to suspend effective operation of said piercer in the more widely spaced reciprocations of said needles.

4. In a sewing machine, a pair of endwise reciprocatory and laterally vibratory needles, needle actuating mechanism including means for reciprocating said needles endwise in unison and for vibrating said needles laterally toward and from each other to perform narrowly and more widely spaced work-penetrating movements, means complementary to said needles in the formation of stitches, work-feeding means, a reciprocatory work-penetrating piercer having its effective operation suspended while out of the work in alternate unison-reciprocations of said needles, and means for actuating said piercer.

5. In a sewing machine, a pair of endwise reciprocatory and laterally vibratory needles, needle-actuating mechanism including means for

vibrating said needles laterally toward and from each other to perform narrowly and more widely spaced work-penetrating movements, means complementary to said needles in the formation of 5 stitches, work-feeding means, a reciprocatory work-penetrating piercer having its effective operation suspended while out of the work in the widely spaced reciprocations of said needles, and means for reciprocating said piercer to penetrate 10 the work in the narrowly spaced reciprocations of said needles.

6. In a sewing machine, a pair of endwise reciprocatory and laterally vibratory needles adapted to perform narrowly and more widely spaced work-penetrating movements, needle-actuating means effective to vibrate said needles laterally while in the work in the narrowly spaced reciprocations of said needles and ineffective to laterally vibrate said needles while in the work in the more widely spaced reciprocations of the needles, a work-penetrating piercer having a path of movement to form apertures in the work for entrance by said needles in their 25 narrowly spaced reciprocations, means for inter-

mittently reciprocating said piercer, and work-feeding means.

7. In a sewing machine, a pair of vertically reciprocatory and laterally vibratory needles adapted to perform unison narrowly and more widely spaced work-penetrating movements, means for actuating said needles, means complementary to said needles in the formation of stitches, work-feeding means effective to advance the work for each of the unison stitch-forming cycles of said needles, a vertically reciprocatory work-penetrating main-piercer having a path of movement to descend into apertures in the work entered by said needles in their narrowly spaced reciprocations, means for intermittently reciprocating said main-piercer, a work-penetrating auxiliary piercer having a path of movement in front of said main-piercer in spaced relation thereto to form work-apertures alternately entered by said main-piercer, and 15 means for actuating said auxiliary piercer to perform work-penetrating reciprocations in each of the unison stitch-forming cycles of said needles. 20

SYDNEY ZONIS. 25
